Primary Examiner — Raphael Barkai(74) *Attorney, Agent, or Firm* — Cantor Colburn LLP(57) **CLAIM**

The ornamental design for part of spectacle frame, as shown and described.

DESCRIPTION

FIG. 1 is a perspective view of part of spectacle frame showing my new design;
FIG. 2 is a front view thereof;
FIG. 3 is a rear view thereof;
FIG. 4 is a left side view thereof, the opposite side view being a mirror image thereof;
FIG. 5 is a top view thereof;
FIG. 6 is a bottom view thereof; and,
FIG. 7 is an enlarged partial view thereof.
Portions shown in broken lines indicate environment and form no part of the claimed design.
